UNITED STATES PATENT OFFICE.

ROBERT LEVI DUTCHER, OF SPOKANE, WASHINGTON.

STRAW-RETARDER FOR STRAW-BURNING FURNACES.

1,111,013.

Specification of Letters Patent. Patented Sept. 22, 1914.

Application filed April 28, 1913. Serial No. 764,134.

To all whom it may concern:

Be it known that I, ROBERT LEVI DUTCHER, a citizen of the United States, residing at Spokane, in the county of Spokane and 5 State of Washington, have invented new and useful Improvements in Straw-Retarders for Straw-Burning Furnaces, of which the following is a specification.

My invention relates to an improvement 10 in straw retarders for straw burning furnaces and has as its principal object the provision of a straw retarder of such design that the same may be used a maximum length of time when burning straw without 15 the retarder being burnt out.

A second object of my invention is to design a straw retarder which shall necessarily be removed when the furnace is using 20 coal or wood in order to prevent any possibility of the retarders being burnt out by the use of said fuel.

A third object of my invention is to design a straw retarder which shall be economical to manufacture and which may be placed 25 in and removed from the furnace with a maximum of convenience.

The final object of my invention resides 30 in the particular arrangement and combination of parts hereinafter described.

In the accompanying drawings which 35 form a part of this specification: Figure 1 shows my improved straw retarder as installed for use with a water leg boiler. It will be understood, however, that it may be adapted for use with any direct flue boiler. Fig. 2 is a detached plan view of my improved straw retarder. Fig. 3 is a side elevation of the device shown in Fig. 2. Fig. 4 is a perspective view of a portion of the device shown in Fig. 2. Fig. 5 is an inverted plan view of a portion of the device shown in Fig. 6 is an inverted plan view of one of the arms of the device shown in Fig. 2.

Throughout the separate views the same part is designated by the same reference characters.

Referring more particularly to the drawings, 1 is a horizontal fire tube boiler of the 45 locomotive type provided with a water leg 2 through which is an aperture 3, the water leg 2 being placed in the fire box 4. In the lower part of the fire box is the usual grate 5 beneath which is an opening 6 controlled 55 by the draft door 7. The front wall of the

fire box is provided with an aperture 8 designed for the introduction of fuel. It is customary when feeding straw to a boiler to insert in the aperture 8 a straw chute such as 9, it being understood that such 60 chute is ordinarily removed when the boiler is being used with coal or wood for fuel. Consequently I have designed my straw retarder so as to be supported wholly by the straw chute 9 so that the retarder will 65 invariably be removed from the fire box when coal or wood is being used. Consequently the danger of burning out my straw retarder because of the intense heat generated by the coal or wood is entirely eliminated.

In order to accomplish the result above mentioned I make my straw retarder in four parts, one of which is a base or support 10, the other three being straw retarding members, such as 11. As indicated in Fig. 1, the member 10 is designed to be used as a support for the members 11 and to be attached directly to the straw chute 9 so that when the latter is removed the entire straw retarder must necessarily be removed from the 80 fire box also. As clearly indicated in Fig. 2, the member 10 is provided with a longitudinal slot 12 into which a bolt such as 13 may be inserted for the purpose of attaching 75 10 to the straw chute 9. It will be understood 85 that because of the slot 12 extending longitudinally of the member 10, the latter may be adjusted longitudinally with relation to the straw chute 9 so as to bring the members 11 into the desired position within the 90 fire box 4. At the left hand end of the member 10 as shown in Figs. 1, 2 and 3, it is provided with two sets of lugs 14—14 and 15—15, respectively, which are clearly shown in Fig. 1 as intended to contact with the upper inner surface of the straw chute 9 so as to hold the member 10 and members 11 in the proper position with respect to the interior of the fire box and the water leg 2. It will be seen that the outer ends of the members 11 are provided with upwardly projecting tips such as 16 which are adapted to contact with the under surface of the water leg 2 so as to prevent the members 11 from being accidentally thrust too far upwardly toward the aperture 3. It is intended, however, that the tips 16 shall not come into use and are provided only for emergency in case of careless adjustment. It is intended that there shall be a space such as is indicated at 17 in 110

Fig. 1 between the tips 16 and the under surface of the water leg 2 and this space 17 I find in practice to be about 1 and $\frac{1}{2}$ inches. As appears clearly, for instance, in Fig. 2, the member 10 comprises a reduced central shank portion 18 and two portions 19 and 20 disposed at opposite ends of the portion 18, the portions 19 and 20 being extended transversely of the portion 18. The portion 19 carries the lugs 14 and 15 previously mentioned and on account of the width of such portion 19 these lugs serve not only to adjust the height of the tips 16, but also prevent the member 10 from rocking about its longitudinal axis. On the upper face of the portion 20 there are provided a plurality of lugs 21 which extend upwardly from the surface of the portion 20 and are bent rearwardly toward the portion 19 so as to form a recess between themselves and the upper surface of the portion 20. The lugs 21 are arranged in pairs with suitable recesses 22 between the lugs of each pair, there being three pairs of the lugs 21, and three of the recesses 22. The members 11, as clearly shown in Figs. 2, 3 and 6, are provided at their left hand ends with a pair of horizontally extending lugs 23 which project transversely from the sides of the members 11 at the ends thereof and are adapted to hook under the lugs 21 as best illustrated in Fig. 3. It will be seen further from Fig. 3 that the members 11 are bent upwardly at each end as indicated at 16 and 24, respectively, and that the right hand edge of the part 20 is extended forwardly as indicated at 25, the members 11 being beveled off immediately beneath the portion 24 so that they are adapted to rest against the inclined surface of the part 25. It will be seen that because of the engagement between the lugs 21 and 23 and also between the portions 24 and 25, that the members 11 are firmly held in position on the member 10 but that they may be readily removed therefrom when desired.

As best indicated in Fig. 5, the member 10 is provided with a web 35 which projects downwardly from the under surface of said member and extends entirely around the same except for an aperture at the left end of the portion 19 immediately under the lugs 15 and for apertures 26 which are immediately under the portion 24 of the members 11. It will be seen that the web 35 forms an inverted trough or channel 27 on the under surface of the member 10, and that air entering the fire box through the straw chute 9 will be guided through the channel 27 and 60 will be delivered under the members 11 through the apertures 26. It will be seen moreover that there will be no tendency for this air to pass up through the slot 12 because the upper surface of the member 10 is 65 in contact with the inner edge of the straw

chute 9 at the point 28. It will be seen from Fig. 6 that the members 11 are provided with downwardly projecting webs such as 29 so that they also have an inverted channel shape and that a slot 30 is provided through which air passing along the under surface of the members 11 may escape upwardly and serve to support combustion above the straw retarders. It will be obvious that air passing along the under surface of the members 10 and 11 as just described will lower their temperature and prolong the life of the fingers 31 which project horizontally on each side of the members or arms 11 for the purpose of preventing straw from passing up through the apertures 3.

It will be obvious that while I have shown and described my straw retarder as applied to a water leg boiler, it may be applied to a boiler without a water leg equally as well.

It will be obvious that while I have shown and described the preferred form of my invention, that various mechanical equivalents may be substituted for the parts shown and described herein without departing from the spirit of my invention, and that I contemplate all such substitutions as will perform the functions of members shown and described herein.

Having thus described my invention, what I claim is—

1. In a straw burning furnace, the combination of a straw chute and a structure adapted to act as a straw retarder having arms projecting into the furnace and adjustably supported on the upper wall of said straw chute and a mounting for said retarder adapted to hold the same in a series of different positions relative to the longitudinal axis of the straw chute.

2. In a straw burning furnace, the combination of a straw chute, a supporting member provided with a longitudinal slot and having lugs adapted to engage the inner surface of said chute, a bolt for holding said member and said lugs against the inner upper surface of said chute, said bolt projecting through said slot and said supporting member being adjustable on said bolt, and arms supported from said member.

3. A straw retarder comprising in combination, a supporting member provided with downwardly depending webs forming an inverted trough or channel, said webs being interrupted at points situated at opposite ends of said member whereby air may pass through said trough, and arms supported by said member having an inverted channel shape, said arms being so positioned as to receive air from certain of the apertures in said web.

4. A straw retarder comprising in combination, a supporting member provided with a shank-like portion and having a portion set at substantially right angles to said

- shank portion, said last mentioned portion being provided with lugs projecting upwardly from its upper surface and turned parallel thereto so as to provide a recess between themselves and the upper surface of said last mentioned portion, and arms provided with lugs adapted to fit into said recesses and be held by said first mentioned lugs.
- 5 10 15 20 25 30
5. The combination of a boiler provided with a fire box, a water leg in said fire box provided with an aperture therethrough, a straw chute for introducing straw into said fire box beneath said aperture, and a straw retarding structure adjustably mounted on said straw chute and projecting into said fire box immediately beneath said aperture, said structure being provided with upwardly projecting tips at its inner end adapted to contact with the upper surface

of the water leg and to thus limit the adjustment of said structure.

6. A straw retarder comprising in combination, a supporting member having an inverted channel shape and arms supported by said member provided with straw retarding fingers, said arms being also of an inverted channel shape and adapted to receive air from said member, said arms being provided with slots near one end thereof whereby air may pass from beneath said arms to the upper side thereof for the purpose of supporting combustion.

In testimony whereof I affix my signature in the presence of two witnesses.

ROBERT LEVI DUTCHER.
